UNITED STATES PATENT OFFICE.

CHARLES L. PAGE, OF AKRON, KANSAS.

LETTER OR PAPER FILE.

SPECIFICATION forming part of Letters Patent No. 470,336, dated March 8, 1892.

Application filed February 18, 1891. Serial No. 381,849. (No model.)

To all whom it may concern:

Be it known that I, CHARLES L. PAGE, a citizen of the United States, residing at Akron, in the county of Cowley and State of Kansas, have invented certain new and useful Improvements in Letter or Paper Files; and I do hereby declare the following to be a full, clear, and exact description of the invention, such as will enable others skilled in the art to which it appertains to make and use the same.

This invention relates to paper-files or temporary holders for current bills, letters, or other papers which ordinarily accumulate in the transaction of business.

The object of my invention, among other things, is to provide a bill-holder in which the retaining device or locking-plate acts at the same time as a perforator for the papers to be filed and to simplify the construction and facilitate the manipulation of the file.

For this purpose my invention consists, primarily, in a bill-file in which the locking-plate for retaining the papers acts in conjunction with the impaling rod or rods to perforate the papers; and my invention consists in such further features, details, and combinations of parts as will be more fully set forth in the following description, and covered in the claims.

In the drawings accompanying this specification, Figure 1 represents the plan of a paper-file embodying my invention; Fig. 2, a vertical longitudinal section; Fig. 3, a vertical transverse section on line xx , and Fig. 4 a detail view.

In the drawings, A represents the base-plate of the paper-file, and B a file-head, which is secured to the base A by screws b or otherwise. The head B comprises the foot b' , the back b^2 , and the ears b^3 . The impaling-rod C are secured to the foot b' at a suitable point, as shown. These impaling-rod C are tubular at their upper portion c' , as shown, for a purpose to be hereinafter explained, and are provided with the upper circular cutting-edges c , produced by beveling the inner surface of the tubular portion c' , as best shown in Fig. 4. This bevel is produced by reaming the tubular portion c' from the inside, and the same may always be sharpened in the same manner.

D is the locking-plate, of metal or suitable material, which is pivoted at d to the ears b^3 . This locking-plate consists of the forward portion d' , having the dies or counter-cutters d^2 arranged so as to register with and pass over and around the cutting-edges c when the locking-plate D is depressed, as shown in full lines in Figs. 2 and 3. These counter-cutters d^2 are preferably formed by reaming the plate D at the proper points, so as to produce the upwardly-made perforations shown, whose lower cutting-edges snugly fit around the impaling-rod C when the plate D is depressed.

I provide means for retaining the locking-plate in its depressed position (shown in full lines in Fig. 2) and in its elevated position. (Shown in dotted lines in the same figure.) These means preferably consist in a spring E, attached to the head B at e and to the locking-plate D, preferably by a link e' , located in a slot e^2 in said plate and large enough to permit the necessary play of the link e' , the link e' being in turn connected with the plate D by the transverse pin or pivot e^3 . The location of this pivot or pin e^3 is such that it will pass the dead-center with the pivot d when fully depressed or when fully elevated. For facility of manipulation I provide the plate D with the tails or arms d^4 .

The head B is preferably cast in one piece, and the impaling-pins C are attached thereto, preferably, by placing them in the flask in any well-known manner and casting the head around them. By this means a firm and compact head is produced, and the rods C will be firmly held in position.

The mode of operation of my paper-file will be obvious from the foregoing.

When it is desired to file a paper, the file is opened by pressing down on the arms d^4 until the pin e^3 has passed the dead-center, when the spring E will hold the plate D open and elevated, as indicated in dotted lines in Fig. 2. The paper is then placed over the rods C and the plate D released by urging the arms d^4 away from the head B until the dead-center is overcome, when the spring E will carry the plate down and by the conjoint action of the cutting-edges e' and the dies d^2 perforate the paper, slip it over the rods C, and lock the file. The plate D thus serves the three purposes of perforating and impaling the papers

and locking them in the file. The openings above the dies d' enable the clippings to be readily removed by blowing or otherwise.

By having the tubular portions c of the impaling-rods C beveled interiorly I am enabled to make the perforations in the papers to be filed in the exact diameter of the said rods. Whenever the cutting-edges become dulled, they are easily sharpened by reaming the tubular portions interiorly.

When the paper-file is filled with papers, or when for any reason it is desired to remove all the papers without disarranging them, the locking-plate D is raised and the staple F is adjusted on the file by inserting its legs f in the tubular portions c of the impaling-rods C , and the papers are then slipped from the impaling-rods onto the staple and may be permanently held in place on said staple when the same is reversed by turning down the projecting ends of its legs f onto the papers.

While I have shown what I consider the preferable form of carrying my invention into effect, it is manifest that the same may be modified in many ways without departing from my invention. I do not, therefore, desire to be limited to the precise construction shown and described; but

What I claim, and desire to secure by Letters Patent, is—

1. In a paper-file, the combination, with an impaling rod or rods, of a locking-plate provided with perforations registering with the impaling-rods, located and secured at the top of the said impaling-rods, substantially as described.

2. In a paper-file, the combination, with impaling-rods provided with upper cutting-edges, of a locking-plate provided with dies or counter-cutters registering with said cutting-edges, substantially as described. 40

3. In a paper-file, the combination of impaling-rods provided with cutting-edges, with a locking-plate provided with upwardly-flaring perforations having cutting-edges at their lower portions, said cutting-edges being adapted to register with and act in conjunction with the cutting-edges of the impaling-rods, substantially as described. 45

4. In a paper-file, the combination, with an impaling rod or rods, of a pivoted locking-plate engaging with the impaling-rods and means for retaining said locking-plate in its open and closed positions, substantially as described. 50

5. In a paper-file, the combination of the following parts: a file-head, a locking-plate pivoted thereto, and a spring attached to the head and to the locking-plate, the parts being so arranged that the spring will retain the locking-plate both in its elevated and in its closed position, substantially as described. 55 60

6. In a paper-file, a file-head comprising an impaling rod or rods and a head proper cast in one piece and around the impaling-rods, substantially as described. 65

In testimony whereof I affix my signature in presence of two witnesses.

CHARLES L. PAGE.
